(57) **CLAIM**

The ornamental design for a large curved wheel leveler, as shown and described.

DESCRIPTION

FIG. 1 is a top, front, right side perspective view of a large curved wheel leveler showing our new design;

FIG. 2 is a bottom, rear, left side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof, the left side elevational view being a mirror image thereof; and,

FIG. 8 is a cross-sectional view taken along lines 8-8 of FIG. 3.

The broken lines illustrate portions of the large curved wheel leveler that form no part of the claimed design.
